(57) CLAIM

The ornamental design for a mobile phone case, as shown and described.

DESCRIPTION

The patent or application file contains at least one drawing executed in color. Copies of this patent or patent application publication with color drawing(s) will be provided by the Office upon request and payment of the necessary fee.

1. Mobile phone case

FIG. 1.1 is a perspective view according to the present invention;

FIG. 1.2 is another perspective view thereof;

FIG. 1.3 is a front view thereof;

FIG. 1.4 is a back view thereof;

FIG. 1.5 is top view thereof; and

FIG. 1.6 is a side view thereof.

The word "Gray" and preceding symbol forming part of the claimed design is a registered trademark of Gray International.
